SIDE BRASS FOR ROLLING MILL HOUSINGS

Filed Aug. 15, 1927

UNITED STATES PATENT OFFICE

CLIFFORD F. PEEK, OF CHESTERTON, INDIANA

SIDE BRASS FOR ROLLING-MILL HOUSINGS

Application filed August 15, 1927. Serial No. 212,957.

My invention relates to improvements in side brasses for rolling mill housings and it more especially appertains to the features pointed out in the claims.

The purpose of my invention is to provide specially formed side brasses for rolling mill housings; that continuously scrape the hard grease toward the outer end of the roller necks; that by reason of a flanged projection which engages the outer diameter of a roller, at its ends, prevents the passage of grease from the bearings onto the surface of the roller; that provides a scraping edge of the brass which continuously engages the roller and neck; that by reason of the beveled upper surface a "reservoir" is provided wherein the hard grease may accumulate; and that may compensate for any reduction in diameter of re-dressed rollers by slightly adjusting the vertical position of the brass.

With these and other ends in view, I illustrate in the accompanying drawing such an instance of adaptation as will disclose the broad underlying principle of my invention without limiting myself to the specific details shown thereon and described herein.

Figure 1 is an end elevation of a pair of rolls in their housing showing the location of the side brasses.

Fig. 2 is an enlarged elevation of the outside end of a side brass.

Fig. 3 is a plan view partly in section showing both ends of a roll.

Fig. 4 is a plan view of Fig. 2.

Fig. 5 is a top plan view showing an adjustable scraping member.

In rolling mill practice where hot rolls are employed it is found necessary to use what is known as a hard grease, of which one of the ingredients is soapstone. This grease is very frequently squashed out from the roller neck bearings on to the surface of the rolls. Even though the rollers are chilled the hard grease leaves indentations in the roll which are transferred to the sheet or other material passing between a pair of rolls. The result is an inferior product and a damaged roll, or perchance a damaged pair of rolls.

It is not only a case of a single pair of rolls being thrown out of commission on ac-

count of such a mishap while one or both rolls are re-dressed, but there may be an entire group of associated rolls in a continuous train that must remain idle while the damage is rectified, thus causing large material losses. To overcome such losses and avoid the necessity of removing grease marks from rolls I provide the side brasses shown on the drawing. In carrying my invention into practice I may use any desired alternative construction that the varying exigencies of daily use may demand without departing from the broad spirit of my invention.

The form which I have found serviceable in actual use comprises a block of brass that is rectangular excepting that its upper face is beveled transversely and longitudinally, one side is made concave to approximate the radius of the roll neck, and the inner end is flanged so as to approximately conform to the outside diameter of the roll. The brasses are made right and left hand so as to serve both ends of a roll. They are placed on the "down" side of roller rotation, respectively for the upper roll on its entry side and for the lower roll on its exit side. Diametrically opposite the special side brasses, ordinary brasses are placed in the housing to receive side strains and assist the top and bottom bearing brasses in holding the rolls in alignment with each other.

In the drawing I have exemplified a housing 1 in which an upper roll 2 cooperates with a lower roll 3. These rolls have necks or spindles 5 which rotate against upper brasses 6 and bottom brasses 7. My improved form of side brasses is identified by the numeral 8. Ordinary side brasses are shown at 9. These side brasses rest in recesses 20 of the housing 1. On the brass 8 a flange 10 is formed on its end. This flange engages the surface of the roll at 19 on a slight bevel (see Fig. 2) which continues toward the neck 5, at 12, along the roller end, as shown in Figs. 2 and 4 and the bevel continues along the fillet 11 thence downward, lengthwise of the neck, at 17, terminating at the outside end of the brass at 13. On the beveled face, between 12 and 13 in the area 14 hard grease may accumulate. The flange 10 may have its

face which is adjacent the roll surface curved at 15 to approximate the curvature of the roll. It is important that the scraping edge 19 engages the surface of rolls 2 or 3. The side of the brass 8 adjacent the roll neck may 5 also be made concave at 16 to approximate the radius of the neck 5.

In case a damaged roll is re-dressed, the slight change in diameter may be compensated for by an adjusting wedge 18 which 10 will lower the brass a small amount to bring the edge 19 into contact with the re-dressed roll surface, or by any other means. This may also be done, if desired, by making the flange 10 separately adjustable through the 15 use of a wedge 18 or any analogous structure which will lower, or otherwise, bring the scraping point 19 against the roller surface to compensate for any change in diameter of the roll in case it is re-dressed.

20 An alternative expedient is shown in Fig. 5, in which flange 10 of Fig. 4 is replaced by a removable scraping member 23, which rests loosely in a groove 21. Any desired form of 25 set screw 22 may be used to adjust the scraping member 23 toward the roll.

What I claim is:

1. In a rolling mill, a housing, a pair of 30 rolls supported therein, a pair of beveled and flanged side brasses for each roll said brasses being positioned adjacent the down side of the roll's rotation in simultaneous engagement with the surface of the roll near its ends, against each end and the necks of the 35 roll to thereby direct grease away from the surface of the roll.

2. In rolling mills, a pair of housings, a pair of rolls supported in the housings, and 40 a pair of side brasses cooperating with each roll, said brasses having beveled upper faces leading toward the outer ends of the roll.

45 3. In side brasses, a suitable member formed with a plurality of concave surfaces on one face thereof formed at different radii, and a flange projecting from the end of the brass over the larger radius concavity, such concave surfaces engaging the neck and face of an adjacent roll to remove foreign substances therefrom as the roll is rotated in 50 engagement with the concave surfaces.

55 4. As an article of manufacture, a side brass comprising a suitable member having a projecting flange at one end thereof, a plurality of different radii concave surfaces on the side of the member, and a top surface that slopes away from the flange toward the concave side and toward the other end of the brass, such concave surfaces engaging the neck and face of an adjacent roll to remove 60 foreign substances therefrom as the roll is rotated in engagement with the concave surfaces.

65 5. In rolling mills, a pair of housings, a pair of rolls supported by the housings, a pair 70 of right and left handed brasses engaging the upper faces of the brasses leading downward toward the outer ends of a roll.

75 6. In rolling mills, a pair of housings, a pair of rolls supported by the housings, a pair of right and left handed brasses engaging the ends of a roll, projecting flanges from the brasses extending toward each other and engaging the surface of a roll, and beveled upper faces of the brasses leading downward toward the outer ends of a roll.

80 7. In rolling mills, a pair of housings, a pair of rolls supported by the housings, a pair of right and left handed brasses engaging the ends of a roll whose upper surface is beveled downward away from the lengthwise center of the roll, and adjustable scraping projections supported by the brasses having their top surfaces sloping toward the ends of the roll.

85 In testimony whereof I affix my signature. CLIFFORD F. PEEK.
